United States Patent

Des. 236,982
Patented Sept. 30, 1975

236,982

DYNAMOELECTRIC MACHINE

Robert F. Gleichman, San Jose, Calif., assignor to General
Electric Company, Schenectady, N.Y.

Filed Apr. 8, 1974, Ser. No. 458,605

Term of patent 14 years

Int. Cl. D13—01

U.S. Cl. D26—5 A

FIG.1

FIG.2

FIG.3

FIG.4

FIG. 1 is a side elevational view of a dynamoelectric machine showing my new design;

FIG. 2 is a top plan view thereof;

FIG. 3 is a side elevational view thereof opposite to that shown in FIG. 1; and

FIG. 4 is a bottom plan view thereof.

I claim:

The ornamental design for a dynamoelectric machine, as shown.
